UNITED STATES PATENT OFFICE.

HERBERT ROLAND MAGUIRE, OF ATHERTON, QUEENSLAND, AUSTRALIA.

PRIVY.

1,425,881.

Specification of Letters Patent. Patented Aug. 15, 1922.

Application filed January 12, 1920. Serial No. 351,008.

To all whom it may concern:

Be it known that I, HERBERT ROLAND MAGUIRE, a subject of the King of Great Britain, residing at Atherton, in the State 5 of Queensland, Commonwealth of Australia, civil engineer, have invented certain new and useful Improvements in and Relating to Privies, of which the following is a specification.

10 This invention relates to the construction of privies and has for its object to provide a hinged false seat, a selfclosing cover to the same and means whereby, when the cover is raised, the false seat shall be raised 15 in a selfacting way to enable the appliance to be used as a urinal.

The invention is applicable to privies used in systems of underground drainage and to dry pans and in the case of the latter 20 provides for the sprinkling, in a selfacting way, of a disinfectant into the pan as the lid closes on the seat.

When installed in systems of deep drainage, the invention will provide means of 25 flushing in a selfacting way.

According to the invention, a false seat is placed upon and hingedly attached to the main seat and a cover or lid is hinged to the false seat that is adapted to spring 30 away from the main seat after use. Behind the false seat is a fixed stop that may be formed with a lower indentation and a knuckle or shoulder, disposed relatively to the lid so that when the latter is raised and 35 the false seat is parallel to the main seat, which will be its position when in use, the lid shall lie against the stop and at about right angles to the false seat, but when the false seat springs away from the main seat 40 the lid or cover shall be caused to impinge against the shoulder of the block and in so doing to be impelled forwards to close upon the false seat.

A suitable spring is attached at its ends 45 respectively to the false and main seats and is designed to lift the false seat when not in use, but its strength will be such that the weight of the lid, when superimposed thereupon, will be sufficient to weigh down the 50 said false seat and to close it upon the main seat of the appliance. When the false seat rises under the influence of the spring it will actuate flushing means in a selfacting way as will hereinafter be described.

55 In the lid will be a canister or other receptacle for holding disinfectant that, as the

lid falls, will be sprayed or sprinkled into the dry pan.

But in order to fully understand the invention reference is made to the accompanying drawing, in which,

Figure 1 is a front elevation of the improved seat as applied in a dry system, the false seat being shown open.

Figure 2 is a side elevation of Figure 1 65 and shows the relative positions of false seat and lid in position for use.

Figure 3 indicates in side elevation the position of the false seat as it rises under the influence of its spring to meet the lid 70 and to cause the latter to be inclined forwards to close over upon it, and,

Figure 4 illustrates the invention as applied to a porcelain pedestal used in deep or underground systems of drainage.

Figure 5 is an enlarged view of the lid and false seat connections.

Figure 6 shows in side elevation the parts employed in the self flushing means with the lid and false seat closed, the dotted lines 80 indicating the position of the parts when the false seat opens.

Figure 7 is a perspective view of the flush actuating lever.

The false seat 7 is hinged to the fixed or 85 main seat 8 at 9 and the lid or cover 10 to the false seat on the inside at 11. Behind the rear edge of 7 is the block or stop 12 that is fixed about midway of the width of the lid 10. The stop may consist of a metal or 90 other web plate with a frontal flange 13, and with a recess at its lower end to provide the shoulder or knuckle 14, the function of which will hereafter be explained, and the position of which should be just behind the 95 rear edge of the lid.

In the centre of the lid 10 a disinfectant receptacle 16 is placed, the floor of which is 100 perforated over about one half its area. The perforations are preferably in the front or upper half of said floor thereby leaving the other half solid to constitute a pocket for the disinfectant powder when the lid is raised. When, however, the lid closes the powder will be projected forwards over the 105 perforations and will fall through same into the pan below. There may, if desired, be an annular projection 17 below the disinfectant receptacle on the lid to cover the delivery of 16 and to retain, for the time 110 being, powder that may escape as the lid is raised. For this purpose the mouth or

opening of the member 17 will be of lesser diameter than the base.

A spring 15 is placed at the side of the appliance or at both sides if desired, and is attached at its ends respectively to the main and false seats. The tension of the spring or springs will be such that same will raise the false seat 7, after the cover is lifted, to a position at an angle of about 70 degrees with the fixed part 8, but when the lid or cover closes over it the combined weight of the false seat and cover will be sufficient to overcome the spring or springs and the parts 7 and 10 will be lowered gently to the position indicated in Figure 4.

One of the objects of the invention is to provide a cover or lid that will be self closing and to that end the parts have been devised and arranged.

If the false seat be relieved of the weight of the lid the spring or springs will react to raise it, but if it be pressed down to the horizontal position and occupied, the springs are again compressed. The lid 10 is then in the position shown in Figure 2 which is one at about right angles to the occupied seat, in which position it will lie flush or parallel with the face of the flange on the stop 12, with the button 18, that may be fixed to the lid, within the recessed or undercut part of the stop and below the shoulder 14.

It will be understood that the lid 10 is hinged to the false seat at a point a little forward of the point where the parts 7 and 8 are hinged together which allows for a certain amount of leverage between the false seat and lid equal to the distance between their respective hinges. When therefore the seat is no longer in use and the spring 15 reacts to raise it, it being borne in mind that the two parts immediately prior to the false seat rising were at right angles to each other and the lid against the stop 12, the upward movement of the false seat will cause the rear edge of the lid to be canted backwards and upwards into the recess in the stop. As the upper part of the lid is against the fixed stop it follows therefore that the lid will be brought into intimate contact with the knuckle 14 and thereby impelled forwards to meet the rising false seat on which it will rest, covering the opening therein and sprinkling the disinfectant powder into the pan as the lid and seat 7 close on the part 8.

The appliance may be used as a urinal and cleanliness and hygiene observed by the spring or springs 15 causing the false lid to widely open immediately the cover 10 is lifted, thereby disclosing the open pan or pedestal, as the case may be, to the user; if, after use, the lid be inclined forwards, the whole will close in the manner above explained.

Referring to the self flushing device as illustrated in Figures 6 and 7, the false seat 7 is fitted at one side with a plate 19 that extends for some distance beyond the rear edge of 7 and is fashioned as indicated in Figure 7. The outer end of the member 19 is shaped as a sector and is provided with the holes 20 in any one of which the end of the flushing chain 21 can be held by the bolt 22.

The object of this arrangement is to provide for adapting the invention to various makes of flushing apparatus in which the bell of one may require to be lifted further than in others to actuate the flush or a longer pull may be required. By connecting the chain 21 in a hole selected in the lever end the travel of the chain can be regulated and the length of pull varied. In the chain near the top a weight 23 is connected which weight is only slightly lighter than the weight required to lift the flushing bell in the cistern. Thus, if the bell will need a 6 pound pull to lift it the weight 23 will be about 5½ pounds in weight, the balance of weight required to start the flush being supplied by the reaction of the spring 15 when the lid 10 is lifted. Thus, when the false seat rises under the influence of its spring, the lever 19 will be rocked and the chain pulled to effect the flush.

It will be evident that the end of the lever 19 may be supplied with additional weight sufficient to act in place of the spring 15, the whole of the parts being disposed and arranged almost in equilibrium so that when the false seat is relieved of the weight of the lid 10 the parts will operate as the seat moves upwards. Should it be necessary, additional weights may be added according to the pull required to operate a particular make of flushing bell. When the appliance is to be used as a urinal the lid 10 will be lifted by hand when the spring 15 will widely open the seat 7 to operate the flush.

I do not confine myself to the exact form of fixed stop 12 as shown which is designed as a support for the raised lid as well as a means for impelling the same forwards when its lower end is raised and canted inwards as the false seat rises. Any fixture in the position of the part 12 and upon which the lid can be rocked may be employed but the form of stop as shown has been found convenient and efficient.

Having now described my invention what I claim as new and desire to secure by Letters Patent is:—

1. In a privy, in combination, a false seat hinged to the main seat and a lid hinged to the false seat slightly forward of the false seat hinges, a fixed stop on the main seat immediately behind the rear edge of the lid against which the lid can come when

open, a lower frontal recess in the stop and a knuckle thereon against which the lid impinges when the false seat rises after being used.

5. 2. In a privy, in combination, a false seat hinged to the main seat, a lid hinged to the false seat, a fixed stop on the main seat behind the lid against which the lid can come when open, a lower frontal recess in the stop, a knuckle thereon and a disinfectant receptacle in the lid in the floor of which receptacle are perforations, for the purposes explained.

10 3. In a privy, in combination, a false seat hinged to the main seat, a lid hinged to the false seat, a fixed stop on the main seat behind the lid against which the lid can come when open, a lower frontal recess in the stop, a knuckle thereon, a disinfectant receptacle in the lid, a floor to the receptacle that is one half perforated and a lower annular projection from the lid below the said receptacle, as and for the purposes specified.

15 4. In a privy, in combination, a main seat, a false seat hinged thereto, a spring or springs between the main and false seats, a lid hinged to the false seat slightly forward of the hinges thereof, a stop on the main seat behind the lid against which the lid leans when at about right angles with the false seat, a frontal recess in the lower part of the stop and a knuckle thereon against which the lid impinges

when the false seat is raised from the main or fixed seat.

5. In a privy, in combination, a false seat hinged to the main seat and a lid hinged to the false seat slightly forward of the false seat hinges, a fixed stop on the main seat immediately behind the rear edge of the lid against which the lid can come when open, a lower frontal recess in the stop and a knuckle thereon against which the lid impinges when the false seat rises after being used, a disinfectant receptacle in the cover or lid, a floor to the receptacle that is one half perforated and a lower annular projection from the lid below the receptacle, as herein specified.

20 6. In a privy, in combination, a main seat, a false seat hinged thereto, a spring or springs between the main and false seats, a lid hinged to the false seat slightly forward of the hinges thereof, a stop on the main seat behind the lid against which the lid leans when at about right angles with the false seat, a frontal recess in the lower part of the stop and a knuckle thereon against which the lid impinges when the false seat is raised from the main or fixed seat and a button on the lid, for the purposes set forth.

In witness whereof I affix my signature.
HERBERT ROLAND MAGUIRE.
